US00D928180S

(12) **United States Design Patent** (10) **Patent No.:** **US D928,180 S**
(45) **Date of Patent:** **** Aug. 17, 2021**

(54) **ELECTRONIC DEVICE WITH GRAPHICAL USER INTERFACE**

(71) Applicant: **Apple Inc.**, Cupertino, CA (US)

(72) Inventors: **Anton Davydov**, Gilroy, CA (US);
Jane E. Koo, Campbell, CA (US);
Wyatt R. Mitchell, San Francisco, CA (US); **Daniel J. Wiersema**, San Jose, CA (US)

(73) Assignee: **Apple Inc.**, Cupertino, CA (US)

(**) Term: **15 Years**

(21) Appl. No.: **29/702,393**

(22) Filed: **Aug. 19, 2019**

Related U.S. Application Data

(63) Continuation of application No. 29/625,171, filed on Nov. 7, 2017, now Pat. No. Des. 857,033.

(57) **CLAIM**

The ornamental design for an electronic device with graphical user interface, as shown and described.

DESCRIPTION

FIG. 1 is a front view of an electronic device having a display screen with graphical user interface applied to the display screen, showing the claimed design; and, FIG. 2 is a front view of another electronic device having a display screen with the graphical user interface design of FIG. 1 applied to the display screen.

The outer broken lines in the figures show an electronic device having a display screen, and form no part of the claimed design. The other broken lines in the figures show portions of the graphical user interface that form no part of the claimed design.

1 Claim, 2 Drawing Sheets
